UNITED STATES PATENT OFFICE.

FRANK S. INGOLDSBY, OF ST. LOUIS, MISSOURI, ASSIGNOR TO THE INGOLDSBY AUTOMATIC CAR COMPANY, OF ST. LOUIS, MISSOURI, A CORPORATION OF WEST VIRGINIA.

DUMP-CAR.

1,048,312.

Specification of Letters Patent. Patented Dec. 24, 1912.

Application filed August 25, 1902. Serial No. 120,959.

To all whom it may concern:

Be it known that I, FRANK S. INGOLDSBY, a citizen of the United States, residing at St. Louis, in the State of Missouri, have invented a certain new and useful Improvement in Dump-Cars, of which the following is a full, clear, and exact description, reference being had to the accompanying drawings.

10 The object of this invention is to produce a very light and strong railway car; the principles of the invention are particularly adaptable to dump cars of the type known as the "Ingoldsby dump car" though the invention is not limited thereto. Such type of car is illustrated in Patents Nos. 551,319, 613,279, and 632,650, granted to me Dec. 10, 1895, Nov. 1, 1898, and Sept. 5, 1899, respectively; it has sides, preferably trussed 15 or girder, and a central longitudinal beam to which there are hinged dumping doors swinging downward at their outer edge.

As the car has been heretofore constructed, the central beam has carried half of the load, and each of the sides a quarter of the load, each bolster thus receiving at its center one fourth of the load and at each end one eighth. Heretofore I have braced the longitudinal central beam by trussing beneath it to enable it to carry half the load, but as the car sides must necessarily be of considerable height to form said walls for the load, I have determined to avail myself of their strength to carry a portion of the load heretofore carried by the central beam. I do this by dividing the central beam in two and resting its ends at the middle of the car on a cross beam carried by the sides, so that the two sides, (in addition to their half of the load) together carry one half of the load on the central beam, that is, for each side one eighth of the entire load in addition to the one fourth heretofore carried, making each side carry three eighths of the load, 45 wherefore each bolster carries at its center one eighth of the load and at each end three sixteenths. The value of this arrangement is evident when it is remembered that the strength of a beam increases as the square of its depth, and that the car sides may be made (and simply for purposes of retaining the load should be made) much deeper than it

is possible to make a central truss without carrying the central beam up unduly high into the car, wasting space, or unduly raising the center of gravity of the whole car.

55 The present invention consists of such an apportionment of the strains, and the means by which I am able to accomplish it, resulting in doing away with any truss for the central beam, and lightening and simplifying the construction. This is clearly illustrated herein in the drawings and is herein-after fully explained.

60 In the drawings, Figure 1 is a side elevation of a little over one half a car embodying the present invention; Fig. 2 is a longitudinal section of such car from the other end, the section being taken at one side of the center as indicated by the line 2--2 of Fig. 3; Fig. 3 is an end view of the car, half of it being in vertical section. Fig. 4 is a bottom plan of a portion of a car at the middle thereof, and Fig. 5 is a top plan of such portion. Fig. 6 is a transverse section 65 of the car at the center. Fig. 7 is a cross section of the central beam, being on the line 7--7 of Figs. 5 and 6. Figs. 8 and 9 are diagrams illustrating the distribution of the weight of the load in the present form of 70 car and in my earlier form, respectively.

75 The sides A of the car are plate girders composed each of sheet steel plates a , an upper chord a' , lower chords a^2 a^3 , and struts a^4 , a^5 , riveted to the plates. At the 80 ends of the car there are inclined floors B riveted to the girder plate of the sides. At the upper end of this inclined floor is an upper cross beam C and beneath this beam is the bolster D. The struts a^4 are secured 85 to the ends of the bolster. Secured to the side girder and to the bolster are the projecting longitudinal beams C' secured to the end sill C² and braced by diagonal posts C³. Running from the end of the car are 90 suitable draft plates E which are secured to the bolster, and from the junction of these draft plates with the end sill are diagonal beams C⁵ running through the bolster to the 95 girder sides. The specific form of this much 100 of the construction does not enter into the present invention.

At the middle of the car on the inner side of each girder plate a , I prefer to rivet tri-

angular strengthening plates G, and extending crosswise of the car I place the beam H which for dump cars preferably is an inverted V-shaped plate having its ends h flanged outwardly and riveted to the sides through the intermediate strengthening plates. This cross beam is given depth by the angle beams J riveted to it and bowing down toward the center of the car.

10 The central longitudinal beam is designated N. As heretofore stated, in the present invention this is divided into two parts each being supported at one end by a bolster D and at the other end by the central cross beam H, where they are connected by the underrunning splice plate n. The beam N consists of an inverted V-shaped sheet metal plate (of as many sheets as desired) strengthened by suitable cross braces P, P', 15 P². At the bolster end, these longitudinal beams extend across the center frame d of the bolster between that frame and the tension strap d' thereof, these three parts being riveted together. The bolster may have 20 a lower channel member d² and intermediate struts d³ and braces d⁴, as shown. The draft plates E are riveted to the central frame d of the bolster and extend inward forming cantalivers, and are riveted to the 25 longitudinal beam N being stiffened by suitable stiffeners e riveted to the draft plates. These features of the connection of the central beam directly with the bolster and with the draft plates, as just described, are shown, 30 described and claimed in Patent No. 35 747,431, issued December 22, 1903 to myself and Joseph R. Bowling, and will not be herein further described.

At the center of the car, as stated, the 40 two sections of the longitudinal beam N are secured to the cross beam H. This is accomplished by connections n' beneath the longitudinal beams, riveted to them and to the cross beam. In order to take the buffing 45 and tugging strains directly through the longitudinal center of the car, as well as to brace the cross beam H, I provide a pair of plates Q which continue the planes of the longitudinal beams within the cross beam 50 H, these plates being flanged inwardly at their ends q and being riveted in place, the same rivets passing through these flanges q through the cross beam H and through the angles n'. This construction makes a 55 very rigid structure for the longitudinal strains, while the weight on the longitudinal beams at the center is transferred to the sides of the car.

Now, in the above described construction, 60 that portion of the load which would primarily come on the central beam (that is, half the entire load), has half (one fourth the entire load) taken by the cross beam H, the other quarter of the entire load being

distributed to the two centers of the bolsters, one eighth each. The quarter of the entire load carried by the central beam is distributed to the two sides, so that each side carries its own quarter of the load, and the eighth of the load received from the 70 central cross beam, making three sixteenths and thus distributing to each end of each of the bolsters three sixteenths of the entire load. The central longitudinal beam being thus relieved of half its work may be made 75 sufficiently rigid without any trussing whatsoever, being simply braced by the cross braces which are otherwise necessary to form the supports for the floor hinges. The result is that a simpler car is produced, and 80 one of fewer parts and much lighter, the load being distributed to the parts which are necessarily of such size as to carry it.

The distribution of the weight is clearly illustrated in the two diagrams, which 85 may be considered as beams resting on top of each other and corresponding to the bolsters, sides and longitudinal and transverse beams, as indicated. In the older form of car illustrated by Fig. 9, half of the load 90 is borne by the central beam, and carried directly to the center of the bolsters, $\frac{1}{4}$ each; and a quarter of the load is borne by each car side, $\frac{1}{8}$ coming onto each end of each bolster.

In the new form, illustrated in Fig. 8, 95 each half of the longitudinal beam carries $\frac{1}{4}$ of the load, distributing $\frac{1}{8}$ to the center of each bolster and $\frac{1}{8}$ from each half longitudinal beam to the cross beam; the cross beam therefore carries $\frac{1}{4}$ of the load, distributing $\frac{1}{8}$ to each car side, wherefore the car sides carry, in addition to their own $\frac{1}{4}$, $\frac{1}{8}$ from the cross beam, making $\frac{3}{8}$ on each side, distributing $\frac{3}{16}$ to each end of each bolster. 105

The dumping doors S are hinged by floor beams S' to the various braces P, P', P² carried by the longitudinal beams. These doors, which are adapted to swing downward between sector-shaped shields V, may 110 be secured in closed position by locking mechanism, and after being dropped they may be elevated by suitable raising mechanism. The locking and raising mechanisms (designated generically T and U, respectively) are fully shown in the prior patents referred to and will not be herein further described. The braces P carry the toggles of the raising mechanism, and the braces P' bumpers for the doors. Each of these 115 braces consist of pairs of uprights p and castings p' duplicated on opposite sides of a plate p² through which they are riveted together.

Having described my invention, I claim: 125

1. In a car, the combination of sides, a central cross beam connecting the same, bolsters connected to the car sides, and a pair

of longitudinal beams each supported at one end by the bolster and at the other end secured to the cross beam.

2. In a car, the combination with sides, a single intermediate cross beam connected to the sides and dividing the car into a plurality of hoppers, an intermediate longitudinal beam or sill extending from bolster to bolster and dividing the car into hoppers, said longitudinal beam being transversely divided, the divided ends being supported by the cross beam, and draft plates connecting the bolsters to said longitudinal beam or sill, substantially as described.

15 3. A car having an intermediate longitudinal beam or sill extending from bolster to bolster and dividing the car into hoppers on each side thereof, said beam being transversely divided at the center of the car, the divided ends of the beam being supported from the side structure and draft plates connecting the bolsters to said longitudinal beam or sill.

25 4. A car having a continuous cross sill located at the center of the car and dividing the car into hoppers at each side thereof, and a longitudinal sill extending from bolster to bolster and dividing at the center, the divided ends being supported by the cross sill, said longitudinal sill being of ridge form, and draft members connected to the bolster and to the under side of said ridge.

35 5. In a car, the combination of sides, a central cross beam connecting the same, bolsters connected to the car sides, and a pair of longitudinal beams in alinement each having one end extending across and secured to one of the bolsters, the other ends being secured to the cross beam, said longitudinal beams extending above the bolsters.

40 6. A dump car having a bolster, car sides, and a central longitudinal beam supported at one end by the bolster and at the other end by a cross beam carried by the sides, and dumping doors hinged to said longitudinal beam.

45 7. A dump car having bolsters, car sides, a central cross beam connecting said sides, a pair of longitudinal beams secured each at its outer end to a bolster and having its inner end resting on and supported by the cross beam.

50 8. A dump car having a bolster, car sides, a cross beam connecting said sides, a longitudinal beam secured to the bolster and to the cross-beam, and cross braces beneath and secured to said longitudinal beam.

55 9. In a car, the combination with the car sides, of a hollow metal cross beam secured to the sides, a pair of longitudinal beams terminating at the outer surface of said cross beam and secured to it, and plates within the cross beam forming a continuation of

the longitudinal beams and transmitting the 65 buffing and tugging strains from one of the longitudinal beams to the other.

10. In a car, the combination of a hollow cross-beam, a pair of longitudinal beams secured to said cross beam, plates within the 70 cross beam forming a continuation of the longitudinal beams through the same and adapted to transmit the buffing and tugging strains through the cross beam from one of said longitudinal beams to the other. 75

11. In a car, the combination of a cross beam, a pair of longitudinal beams secured to said cross beam, braces secured to the cross beam, said braces spanning the junction of the cross and longitudinal beams and 80 flaring downwardly at such junction.

12. In a car, the combination of a cross beam, a pair of longitudinal beams secured to said cross beam, plates within the cross beam secured thereto and forming a continuation of the longitudinal beams therethrough, braces secured to the cross beam, 85 said braces spanning the junction of the cross and longitudinal beams and flaring downwardly at such junction. 90

13. The combination of a car having plate sides, of a cross beam consisting of an inverted V-shaped plate riveted to said sides, and longitudinal beams resting on the cross beam and extending each way therefrom 95 and secured to the cross beam, and plates beneath the cross beam in the same plane as the longitudinal beam and riveted to the cross beam.

14. The combination of a dump car having plate sides, of a cross beam consisting of an inverted V-shaped plate riveted to said sides, and longitudinal beams resting on the cross beam and extending each way therefrom 100 and secured to the cross beam, said longitudinal beam being an inverted V-shaped plate, connections beneath it for securing it to the cross beam, and plates beneath the cross beam in the same plane as the longitudinal beam, said plates being 105 flanged at their ends and held in place by the same rivets which secure the connections to the cross beam. 110

15. In a car, the combination with the sides, of a cross beam made of an inverted 115 V-shaped plate the sides of which are stiffened by depending angle bars riveted thereto, said bars flaring downwardly toward the center of the car.

16. In a car, the combination with plate 120 sides, of reinforcing plates adjacent thereto, and a cross beam flanged at its ends, and rivets passing through such flanges, the reinforcing plates and the car sides.

17. In a car, the combination with plate 125 sides, of triangular reinforcing plates secured thereto with the apices of the triangles extending upwardly, and a cross beam

4
having flanges at its ends riveted to the reinforcing plates.

18. In a car, the combination of plate girder sides, a cross beam in the form of an inverted V-shaped plate extending through from side to side and riveted to the sides, and stiffened by bars riveted to it, and a pair of longitudinal beams also of inverted V-shaped plates and stiffened by braces beneath them and resting upon said cross beam, and connected together over the top thereof and secured by rivets to the cross beam, and plates within the cross beam riveted to it and substantially in alignment with the longitudinal beams.

19. In a car, the combination of plate girder sides, a sheet metal cross beam riveted thereto, bolsters to which the sides are secured, and longitudinal beams riveted to the cross beam and connected to the bolsters, said longitudinal beams being braced by members riveted to their under sides.

20. In a car, the combination of the sides, a cross beam secured thereto, bolsters, longitudinal beams secured to the cross beam and to the bolsters, and cross braces secured to said longitudinal beams.

21. In a car, the combination of plate girder sides, a metal beam riveted thereto, and longitudinal beams resting upon and riveted to said cross beam, said longitudinal beams being provided with cross braces.

22. A car having a bolster, car sides, a cross beam connecting the sides, a longitudinal beam secured to the bolster and the cross beam, said cross beam including a reinforced member bent downward intermediately and lying beneath the longitudinal beam.

23. In a car, the combination with the sides, reinforcing members secured thereto on their inner sides, a longitudinal beam, a cross structure secured to said reinforcing members and to the longitudinal beam, and including a reinforcing structural brace bent downward intermediately of its ends and passing beneath the longitudinal beam.

24. In a hopper bottom car, a longitudinal deflecting crown extending past a plurality of hopper openings, a supporting means therefor comprising plate girder sides, a continuous member connected with said sides and a central longitudinal member divided at the cross member and connected therewith.

25. In a hopper bottom car, a longitudinal deflecting crown extending past a plurality of hopper openings, plate girder sides, a continuous cross deflecting crown secured to the sides and extending past hopper openings laterally, the longitudinal deflecting crown being supported at its center by the cross crown.

26. The combination of a longitudinal deflecting crown extending past a plurality

of hopper openings, and supporting means 65 therefor comprising plate girder sides and a continuous cross member located at the center of the car and connecting its sides by extending continuously between the same.

27. The combination, in a car, of plate 70 girder sides, a continuous cross structure at the center of the car extending from side to side and including a shedding ridge dividing the car into hoppers in each side thereof, and longitudinal central sills extending 75 from the bolster and resting at their inner ends on and carried by such cross structure.

28. In a car, the combination of plate 80 girder sides, a cross beam of inverted V-shape extending from side to side of the car, and longitudinal beams of inverted V-shape supported at the bolsters and at the center of the car.

29. In a hopper bottom car, plate-girder 85 sides, sectional center sills in the form of a shedding ridge extending in substantially the same plane from end to end, and a continuous cross girder supporting said center sills, said girder being connected with said 90 sills and said plate-girder sides and adapted to support said deflecting crown, substantially as described.

30. In a hopper bottom car, the combination of longitudinal center sills in the form 95 of a shedding ridge, and a transverse girder adapted to support said sills near the middle of the car, hopper doors, means for supporting said doors normally away from the hopper discharge opening and means for closing 100 said doors, substantially as described.

31. In a hopper-bottom car, plate girder sides, continuous bolsters connected therewith, draft-sills connected with said bolsters, sectional center sills, a cross girder in the 105 plane of said sills connected thereto and with said plate-girder sides, and braces connected with said sides in alignment with said cross-girder, substantially as described.

32. In a hopper bottom car, plate-girder 115 sides, sectional center sills in the form of a shedding ridge extending in substantially the same plane from end to end, and a continuous cross-girder in the plane of said center sills, said girder being connected with 120 said sills and said plate-girder sides, and adapted to support said deflecting ridge, substantially as described.

33. In a hopper-bottom car a longitudinal central member downwardly sloping at its 120 top, a transverse member intersecting said longitudinal member at the center and adapted to support the same, hopper doors and door end guards therefor depending from one of the said members, and means 125 for closing said doors substantially as described.

34. In a car, the combination of plate

girder sides, a bolster near each end of the car, said bolsters connected to the car sides, a central cross beam connected to the car sides, and a longitudinal beam secured to 5 the bolsters and the central cross beam and extending above such beam.

35. In a car, the combination of plate girder sides, a bolster near each end of the car, said bolster connected to the car sides, 10 a central cross beam of inverted V-shape, and a longitudinal beam secured to the bolsters and the central cross beam, said longitudinal beams extending above the bolsters.

36. In a car, the combination of plate 15 girder sides, a cross beam of inverted V-shape extending from side to side of the car, and longitudinal beams secured to the bolsters and supported thereby and at the center of the car.

20 37. In a car, the combination of plate girder sides, a cross beam extending from side to side of the car, and longitudinal beams of inverted V-shape supported at the bolsters and at the center of the car.

25 38. In a car, the combination of plate girder sides, a central cross beam connecting the sides, said beam being of inverted V-shape, and two longitudinal beams in alignment, said beams being supported at their 30 inner ends by the central cross beam.

39. In a car, the combination of plate 35 girder sides, a central cross beam connecting the sides, and two longitudinal beams in alignment supported at their inner ends by the central cross beam, said longitudinal beams being of inverted V-shape.

40. In a car, the combination of a central cross beam, two longitudinal beams in alignment on opposite sides of the cross beam, 40 said longitudinal beams being connected together over the cross beam.

41. In a car, the combination with the sides, of a central cross beam connected thereto, two longitudinal beams on opposite 45 sides of the cross beam, and a member in addition to the cross beam connecting the longitudinal beams.

42. In a car, the combination with a cross beam, of longitudinal beams on opposite 50 sides thereof rising higher than the cross beam, and a split plate over the top of the cross beam connecting said longitudinal beams.

43. In a car, the combination with the 55 sides, of a cross member, longitudinal members on opposite sides of the cross member, said longitudinal members being divided at the cross member, members intermediate of the cross member alining with the said 60 longitudinal members, and means in addition to the cross member and said intermediate members for connecting the divided portion of the longitudinal members.

44. In a car, the combination with the

sides, of a cross member of ridge form, reinforces along the lower portions of such cross member, longitudinal members of ridge form on opposite sides of the cross member, and inclined distance pieces within the cross member alining with the longitudinal members. 65 70

45. In a car, the combination with the sides, of a cross member of ridge form, reinforces along the lower portions of such cross member, longitudinal members of ridge 75 form on opposite sides of the cross member, and inclined distance pieces within the cross member alining with the longitudinal members, the longitudinal ridges rising higher than the cross ridge and extending over such 80 cross ridge and being there connected.

46. In a car, the combination with a central cross member united at its opposite ends to the sides of the car, a central longitudinal beam divided at its center but extending 85 over the cross member and supported at the central ends by the cross member and supported at its opposite ends by the bolsters of the car.

47. In a car, the combination with a central cross member united to the sides of the car, and a central longitudinal member divided at its center, the central ends of said longitudinal beam abutting against each other, a member beneath the ends of the 95 longitudinal beam joining them together, the opposite ends of the longitudinal beam being supported by the bolsters of the car.

48. In a car, the combination of a continuous central cross member extending from 100 side to side of the car, an inverted V-shaped longitudinal beam divided at its center, the adjacent central ends of the divided longitudinal beam being joined together, the opposite ends of the beam being supported by 105 the bolsters.

49. In a hopper-bottom car, a sectional center member, plate girder sides and cross member connected with said sides and with 110 said center member, continuous bolsters and draft mechanism between the same and the ends of the car.

50. In a hopper-bottom car, sectional center sills, plate girder sides, a cross girder in the plane of said center sills connected 115 with said sills and said plate girder sides, bolsters connected with said sectional center sills and draft sills between said bolsters and the ends of the car.

51. In a hopper-bottom car, plate girder 120 sides, continuous bolsters connected therewith, sectional center sills, a cross girder in the plane of said sills connected thereto and with said plate girder sides, and stiffening members connected with said sides in 125 alinement with the cross girder.

52. In a hopper bottom car, the combination of plate girder sides, continuous bol-

sters connected therewith, draft sills connected with said bolsters, center sills, a cross girder connected with said center sills and with said plate girder sides, and braces for the cross girder.

53. In a hopper bottom car, the combination of plate girder sides, bolsters connected therewith, longitudinal center sills having a deflecting ridge, a continuous cross girder 10 connected with the sides and intersecting the longitudinal center sills, and a pair of braces

connected with the cross girder in the opposite sides of the center sills and extending continuously from one side of the longitudinal sill to the other side.

15
In testimony whereof, I hereunto affix my signature in the presence of two witnesses.

FRANK S. INGOLDSBY.
